MAGNETIC GUN RECOIL PAD STRUCTURE

Norman A. Bivens, North Hollywood, Calif.

Application June 13, 1958, Serial No. 741,858

7 Claims. (Cl. 42—74)

This invention relates to improvements in quick detachable gun butt recoil pads, and more particularly to improved gun recoil pad structures of this kind wherein the recoil pads are removably secured on their gun butts by magnetic attraction.

The primary object of the invention is to provide magnetically secured recoil pads for gun butts which can be more quickly and easily interchanged in the field, the recoil pads being sufficiently strongly secured to the gun butts to preclude their coming off under any conditions or accidents ordinarily met with in the field, but being capable of being easily removed by manually pulling the recoil pads in a rearward direction away from the gun butts.

Another object of the invention is to provide magnetic recoil pad structures of the character indicated above having mechanical parts, and involve magnetic sockets and non-magnetic plugs on bosses removably engageable therein with magnetic armature plates surrounding the plugs, which are interchangeably securable either on the recoil pads or on the gun butts, so that the structures can be more suitably accommodated to different recoil pad and gun butt constructions, such as solid gun butts and cored or hollow gun butts.

A further object of the invention is to provide in structures of the character indicated above, butt caps which have secured on their forward gun butt engaging ends, recoil absorbing pads which involve dual resilient shock-absorbing or cushion plates between which is sandwiched a non-compressible base plate, to which the plugs or the magnetic sockets are secured, the base plate having embedded therein a stiffening plate, in a manner to provide rigid mounting for the plugs or sockets, and to preclude buckling of the recoil pad during removal of the butt cap from a gun stock.

A still further object of the invention is to provide magnetic retaining and positioning means of the character indicated above which can be marketed as a kit for easy application, with a minimum of work and mutilation thereof, the butt caps and gun stock butts, so as to provide therefor quick-detachable magnetic securing of the butt caps to the stocks, at relatively low cost.

Other important objects and advantageous features of the invention will be apparent from the following description and the accompanying drawings, wherein, for purposes of illustration only, a specific form of the invention is set forth in detail.

In the drawings:

Figure 1 is a rear end elevation of a butt cap in accordance with the present invention, the recoil pad stiffening plate, plugs, armature plates, and magnetic sockets being shown in phantom lines;

Figure 2 is a fragmentary vertical longitudinal section taken on the line 2—2 of Figure 1;

Figure 3 is an enlarged fragmentary horizontal section taken on the line 3—3 of Figure 2;

Figure 4 is an exploded perspective view showing related ends of the butt cap and gun stock;

Figure 5 is an exploded sectional view, similar to Figure 2, showing another form of the invention, involving a hollow gun stock; and

Figure 6 is a fragmentary vertical transverse section taken on the line 6—6 of Figure 5.

Referring in detail to the drawings, wherein like or similar numerals designate like parts throughout the several views, and first to Figures 1 to 4, thereof, the numeral 10 generally designates a gun stock having a butt end 12 which is flat; and the numeral 14 generally designates a separable shoulder-engaging butt cap having a forward end 16 having secured thereon a recoil shock absorbing pad, generally designated 18.

The recoil pad 18 consists of a sandwich composed of

15 a rear resilient shock-absorbing or cushion plate 20, shaped conformably to and secured in suitable manner, to the forward end 16 of the butt cap 14, a rigid non-compressible base plate 22, and a forward resilient shock-absorbing or cushion plate 24. The plates 20, 22 20 and 24 are preferably molded of such as neoprene, and colored to disguise and conform their presence between the butt cap 14 and the gun stock 10.

Embedded in and spaced from the upper and lower ends and the side edges of the rigid base plate 22 is a 25 central relatively narrow vertically elongated rigid metal stiffening plate 26, which is preferably of an aluminum alloy, and has grooves 27 in its side edges receiving material of the base plate 22.

Seated in openings 28 provided in the front plate 24 30 at the ends of the stiffening plate 26 and bearing against the front sides of the stiffening plate 26 and the center plate 22, are annular magnetic armature plates 30, whose front surfaces are preferably flush with the front side of the front plate 24. Preferably aluminum alloy posi-

35 tioning plugs or bosses 32 comprise reduced threaded shanks 34 and enlarged diameter heads 36 which define shoulders 38 on the rear ends of the heads 36 which bear against the front sides of the armature plates 30 when the shanks 34 are threaded into openings 40 pro-

40 vided at the ends of the stiffening plate 26, whereby the armature plates 30 and the plugs 32 are secured to the pad 18, with the heads 36 of the plugs projecting forwardly from the pad 18. The plug heads 36 preferably have screwdriver slots 42 in their forward ends 45 for easy installation and removal thereof. The described association of pad 18, stiffening plate 26, armature plates 30, and plugs 32 provides a rigid construction which will not buckle or loosen under field use of a gun or when a butt cap is being secured to or removed from a gun stock at high speed and with a minimum of attention and care.

In the butt or rear end 12 of the gun stock 10 are 50 formed threaded counterbores 44 in which are threadably and removably engaged magnetic sockets 46 having rear ends 48 which are preferably substantially flush with the rear end 12 of the gun stock 10. The magnetic sockets 46 are lined up with the armature plates 30 and the positioning plugs 32, and have therein preferably axial smooth counterbores 50, into which the plug heads 36

55 are conformably and slidably engageable for positioning and retaining the butt cap 14 in perfect alignment with the gun stock 10. The magnetic attraction between the magnetic sockets 46 and the armature plates 30, which are then in contact with each other, is sufficient to hold the plugs 32 in the sockets 46 unless and until sufficient endwise force is exerted to overcome the magnetic attraction. It will thus be seen that separation of the butt cap 14 from the gun stock 10 or connection of the butt cap 14 on the gun stock 10 is a simple matter of 60 unplugging and plugging the butt cap on the gun stock and involves no other operations, mechanical or otherwise.

65

70

In the form of the invention shown in Figures 5 and 6, involving a hollow gun stock 10a having a longitudinal core 52, which makes it preferable and advisable to mount the plugs 32a and the armature plates 30a on the gun stock 10 and the magnetic sockets 46a on the butt cap pad 18a, the plugs 32a have elongated wood screw shanks 34a which are threaded into the open stock butt end 12a with the armature plates 30a bearing against the end 12a and held in place by the heads 36a of the plugs 32a.

The magnetic sockets 46a instead of being plain cylindrical, like the magnetic socket 46 of Figures 1 to 4, the sockets 46a have lateral annular stop flanges 54 on their rear ends. The main parts of the sockets 46a, as shown in Figure 5, are seated in openings 28a in the stiffening plate 26a, with the flanges 54 in openings 56 in the rear plate 20a and in recesses 58 in the butt cap 14a, and with the flanges 54 in stop engagement with the rear side of the stiffening plate 26a.

The sockets 46a have terminal front ends 60 which are preferably flush with the rear side of the front plate 24a, and are registered with openings 62 in the front plate 24a, which are provided to receive the armature plates 30a into contact with the front ends 60 of the sockets 46a.

While there has been shown and described herein a preferred form of the invention, it is to be understood that the invention is not necessarily confined thereto, and that any change or changes in the structure of and in the relative arrangements of components thereof are contemplated as being within the scope of the invention as defined by the claims appended hereto.

What is claimed is:

1. A gun recoil pad structure comprising a gun stock having a butt end, a shoulder-engaging butt cap having a front end, a recoil pad secured on the front end of the butt cap and engaged with the butt end of the gun stock, and magnetic positioning and retaining means comprising separable magnetic components severally secured on the butt end of the gun stock and on said front end of the butt cap and engaged with each other.

2. A gun recoil pad structure comprising a gun stock having a butt end, a shoulder-engaging butt cap having a front end, a recoil pad secured on the front end of the butt cap and engaged with the butt end of the gun stock, and magnetic positioning and retaining means having separable components removably securing the butt cap to the

gun stock, comprising first and second components, said second components comprising magnetic sockets, and said first components comprising positioning plugs removably engageable in the sockets and magnetic armatures operatively connected to said plugs and engageable with the magnetic sockets only while the plugs are in the sockets.

3. A gun recoil pad structure according to claim 2, wherein said plugs are secured in the recoil pad and said sockets are secured in the butt end of the gun stock.

10 4. A gun recoil pad structure according to claim 2, wherein said plugs are secured in the butt end of the gun stock and said sockets are secured in the recoil pad.

15 5. A gun recoil pad structure according to claim 2, wherein said recoil pad comprises a sandwich composed of a rear resilient cushion plate secured to the front end of the butt cap, a center rigid and non-compressible base plate secured to said rear plate, and a front resilient cushion plate secured to said base plate, and a centered relatively narrow stiffening plate embedded in said base plate.

20 6. A gun recoil pad structure comprising a gun stock having a butt end, a shoulder-engaging butt cap having a front end, a recoil pad secured on said front end, said pad having a front end bearing against said butt end, magnetizable sockets fixed in said gun stock and exposed at said butt end, plugs fixed in said recoil pad, said plugs extending forwardly from the front end of the pad and being engaged in said sockets, and magnetic armature plates fixedly surrounding the plugs and engaged with 30 the sockets and magnetically attracting the sockets.

7. A gun recoil structure comprising a gun stock having a butt end, a shoulder engaging butt cap having a front end, a recoil pad secured on said front end, said recoil pad having a front end engaged with said butt end, magnetizable sockets fixed in said recoil pad, plugs fixed on said gun stock and projecting rearwardly beyond said butt end, and magnetic armature plates fixedly surrounding the plugs and secured to the butt end, said plugs being engaged in the sockets and said armature plates being 40 engaged with and magnetically attracted to the sockets.
